[57] CLAIM

The ornamental design for a golf measuring apparatus, as shown and described.

DESCRIPTION

FIG. 1 is a perspective view of a golf measuring apparatus showing my new design; with the measuring tape shown in it's environmental use;

FIG. 2 is an enlarged scale perspective view thereof; with the measuring tape extended out from it's assembly;

FIG. 3 is a top plan view thereof; with the measuring tape in it's retracted position;

FIG. 4 is bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.

The broken line showing of a ball and the flag post is for illustrative purpose only and forms no part of the claim.
